Inventor:
Frederick W. Hottenroth,
By his Attorney, Les. McLean

UNITED STATES PATENT OFFICE.

FREDERICK W. HOTTENROTH, OF PARK HILL, NEW YORK.

TRAFFIC-SIGNALING MEANS FOR VEHICLES.

1,403,032.

Specification of Letters Patent. Patented Jan. 10, 1922.

Application filed August 12, 1921. Serial No. 491,688.

To all whom it may concern:

Be it known that I, FREDERICK W. HOTTENROTH, a citizen of the United States, and a resident of Park Hill, county of Westchester, and State of New York, have invented 5 certain new and useful Improvements in Traffic-Signaling Means for Vehicles, of which the following is a specification.

While applicable to traction vehicles generally, my improved traffic signaling appliances are designed more particularly for use on automobiles and other motor driven vehicles, my object being to afford means, positioned in convenient proximity to the 15 chauffeur, whereby the various exigencies of travel may be quickly and conveniently indicated to those either in advance of or at the rear of the car, so as to obviate collisions and other dangers incidental to road 20 traffic.

To this end the invention consists primarily and essentially in manipulatable means positioned upon or adjacent to the dash board whereby indicators may be advanced or retracted on either or both sides 25 of a car substantially in the manner and for the purposes hereinafter fully set forth.

In the accompanying drawings, I show various mechanical devices and expedients 30 whereby the desired results may be attained in a practical manner, although I do not wish to limit myself to minor details of construction since various modifications may be resorted to without departing from the 35 spirit and intent of my invention in this respect, and with like effects.

Fig. 1, is a diagrammatic representation of a portion of an auto-car adjacent to the dash board thereof, showing a plurality of 40 indicators positioned and protuberant on each side of the car,—the latter being viewed at the angle of inclination of the steering post, and the indicators being shown in side elevation in retracted vertically pendent position for convenience of illustration;

Fig. 2, is a sectional elevation, upon a larger scale, showing details of the indicating means shown in Fig. 1, broken away in part for convenience of illustration;

Fig. 3, is a transverse section on a still larger scale, taken upon plane of line 3—3, Fig. 2;

Fig. 4, is a sectional detail taken on general plane of line 4—4, Fig. 2, showing the 55 gears, etc., at the left end of the indicator

manipulative means represented in the preceding figures of the drawings;

Fig. 4^a, is a similar view showing the gears, etc., at the right hand of the concentric manipulative shafts;

60

Fig. 5, is a detail view of the central portions of the concentric shafts shown in said preceding figures;

Fig. 6, is a sectional detail of said manipulative shafts showing a preferred form of 65 detent for holding said shafts against unintentional rotation;

Fig. 7, is a sectional elevation showing a modification in which trip levers and connecting rods are substituted in lieu of the 70 mitre gears shown in Figs. 1, 2 and 4, of the drawings;

Fig. 8, is a sectional elevation taken upon plane of line 8—8, Fig. 7;

Fig. 9, is a detail of the extremities of one 75 of the connection rods shown in Figs. 7 and 8, indicating the use of a form of ball and socket joint for the pivotal attachment of the rods to the trip levers;

Fig. 10, is a view similar to Fig. 8, illustrating a modification in which eccentrics are substituted in lieu of the lower trip 80 levers;

Fig. 11, is an elevation illustrating the substitution of slotted bell crank levers in 85 lieu of the mitre gears shown in Figs. 1, 2, and 3;

Fig. 12, is a top view of the parts shown in Fig. 11;

Fig. 13, is a perspective view of the parts 90 shown in Figs. 11 and 12;

Fig. 14, is a sectional detail illustrating the use of an indicator disc in lieu of the plurality of indicator arms shown in the preceding figures,—the section being taken 95 upon plane of line 14—14, Fig. 15;

Fig. 15, is a face view of the indicator box shown in Fig. 14;

Fig. 16 is a section of said indicator box taken upon plane of line 16—16, Fig. 14, 100 and showing the indicator disc in elevation.

As hereinbefore intimated various mechanical expedients may be resorted to in the practical application and adaptation of my invention to vehicles of different forms 105 and types, the essential feature being one or more indicators *a*, pivotally supported, and means for advancing and retracting said indicator manually substantially as and for the purposes herein set forth.

110

In the first six figures of the drawings, a plurality of indicator arms a, a , are shown as each rigidly attached to one of a plurality of pivotal journals j, j , mounted in 5 bearings b, b , attached to a bracket support b', b' , on the side of the car, each of said pivotal journals j, j , having also rigidly attached to it a bevel gear g , which meshes with a corresponding bevel gear g' , rigidly 10 mounted on the extremity of one of a plurality of concentric shafts s, s, s , each provided with a handle s^2 , or equivalent means by which the shaft may be turned on its longitudinal axis independent of the other 15 shafts.

Each of these shafts s , is provided with a spring detent d , which prevents the unintentional rotation thereof, and counteracts any 20 tendency of the shaft to follow the movement of any other shaft, while permitting its forcible rotation by hand through the medium of its individual handle h , or other turning means. Two forms of such shaft detent d , are shown by way of exemplification, in the drawings, although I do not 25 restrict myself to the use of either, or any particular form of detent. Thus, in Fig. 3, the detent d , consists of a spring bolt the nose of which engages with a notch in the 30 periphery of its own particular shaft s , whereas in Fig. 6, a spring detent is used which is raised and lowered by a lever d' , fulcrumed on the handle s^2 .

When in normal position the indicators a , 35 are pendent, and may be concealed in such position by a suitable shield. They are turned into visual operative position by a partial rotation of the shaft with which they are connected, so as to protrude outward 40 from the side of the car horizontally, as indicated for instance by the dotted lines a' , Fig. 2. The indicator arms are of course differently marked to designate a turn to the right or left, stoppage, etc., as by means 45 of arrows shown in the drawings, or by any other desired or appropriate characters or designs, or words that will answer the same purpose.

The indicators a , may be provided for one 50 or both sides of the car. When arranged on both sides thereof the mechanisms described are duplicated as indicated in Figs. 1 and 4, the reversal of the gears as shown in Fig. 4, insuring like results on both sides of the 55 vehicle. When both sides of the car are thus equipped, the outer concentric shafts s, s , are slotted medially to accommodate the handles s^2, s^2 , and to admit of the requisite independence of movement of each shaft, as 60 indicated in Figs. 3, 5 and 6.

In Figs. 7 to 9, inclusive, trip levers a^2, s^3 , are substituted in lieu of the mitre gears g, g' , said trip levers a^2, s^3 , being connected 65 with the rods c, c , by means of ball and socket joints c', c' , which allow said con-

nection rods c, c , to adapt themselves to variance in inclination incidental to the fact that the trip levers s^3 , on the actuating shafts s, s , are positioned at right angles to those a^2 , on the indicators a . 70

In the modification shown in Fig. 10, the shaft trip levers s^2 , are replaced by eccentrics s^4 , with like result.

In Figs. 11 to 13 inclusive, slotted rocker arms a^5, a^6 , are substituted in lieu of the 75 bevel gears g , and a slotted reciprocating actuating rod r , is used instead of a shaft, with like result in that the indicators a, a , may be advanced and retracted as desired.

In the modification shown in Figs. 14 to 80 16 inclusive, the indicator a , is in the form of a rotatable disc enclosed in a box or casting h , provided with a sight aperture h' . In this arrangement all the pointers or indicator marks are placed on the face of a 85 single disc, which may be rotated fully in either direction so as to bring the marks successively into coincidence with the sight aperture h' .

What I claim as my invention and desire 90 to secure by Letters Patent is,

1. In traffic signaling means of the character designated, the combination of an indicator arm, rigidly attached to a pivotal journal, a mitre gear rigidly attached to said 95 pivotal journal, a mitre gear meshing with said journal gear and mounted rigidly on a rotatable shaft, said rotatable shaft, and means for turning said shaft manually and means for holding said shaft against unintentional rotation substantially as and for the purpose set forth.

2. In traffic signaling means of the character designated, the combination of a plurality of pivotal journals, a plurality of indicator arms each rigidly attached to said 105 pivotal journals, mitre gears meshing with said journal gears and mounted rigidly each on an independently rotatable shaft, said rotatable shafts concentrically arranged and means for turning each of said shafts manually and individually, substantially in the manner and for the purpose described.

3. In traffic signaling means of the character designated, the combination of a plurality of indicator arms each rigidly attached to its own pivotal journal, mitre 115 gears rigidly attached to said pivotal journals, mitre gears meshing with said journal gears and mounted rigidly each on an independently rotatable shaft, said rotatable shafts concentrically arranged and means for turning each of said shafts manually and individually, together with detent means for holding said concentric shafts 120 against unintentional rotation, substantially in the manner and for the purpose described.

4. In a traffic signaling device of the character designated, the combination of a plu- 130

rality of indicators pivotally mounted, manually operable concentric rotative shafts, and gearing intermediate between said shafts and said indicators whereby the latter 5 may be separately and individually actuated in planes parallel to the common longitudinal axes of said shafts, substantially in the manner and for the purpose described.

5. In traffic signaling means of the character designated, the combination of an indicator disc rigidly attached to a pivotal journal, a mitre gear rigidly attached to

said pivotal journal, a mitre gear meshing with said journal gear and mounted rigidly on a rotatable shaft, said rotatable shaft, 15 and means for turning said shaft manually, together with detent means for holding said concentric shafts against unintentional rotation, substantially in the manner and for the purpose described.

FREDERICK W. HOTTENROTH.
